United States Patent Office

Des. 204,779
Patented May 17, 1966

204,779

ELECTRIC BROILER

David L. Painter, Chicago, Ill., assignor to The West Bend Company, West Bend, Wis., a corporation of Wisconsin

Filed Sept. 1, 1965, Ser. No. 86,796

Term of patent 7 years

(Cl. D44—1)

FIG. 1

FIG. 3

FIG. 1 is a top view of an electric broiler embodying my new design;

FIG. 2 is a view in side elevation thereof; and
FIG. 3 is an end view thereof.

I claim:

The ornamental design for an electric broiler, substantially as shown.
